UNITED STATES PATENT OFFICE

126,187

DESIGN FOR A SIPHON HEAD

Lee Gebhart, Coral Gables, Fla., and Howard L.
Ross, New York, N. Y.

Application October 11, 1940, Serial No. 95,768

Term of patent 14 years

To all whom it may concern:

Be it known that Lee Gebhart and Howard L. Ross, citizens of the United States, residing at Coral Gables, county of Dade, and State of Florida, and New York city, county of New York, and State of New York, respectively, have invented a new, original, and ornamental Design for a Siphon Head, of which the following is a specification, reference being had to the accompanying drawing, forming part thereof, wherein:

We claim:

The ornamental design for a siphon head, as shown.

LEE GEBHART.
HOWARD L. ROSS.
